(57) **CLAIM**

The ornamental design for a frame for agricultural implement, as shown and described.

DESCRIPTION

FIG. 1 is an isometric view of a frame for agricultural implement showing our new design;

FIG. 2 is a top plan view of the frame for agricultural implement of FIG. 1;

FIG. 3 is a front elevation view of the frame for agricultural implement of FIG. 1;

FIG. 4 is a side elevation view of the frame for agricultural implement of FIG. 1;

FIG. 5 is a rear elevation view of the frame for agricultural implement of FIG. 1; and,

FIG. 6 is a bottom plan view of the frame for agricultural implement of FIG. 1.

The broken lines contained in any of the drawings form no part of the claimed design.
